United States Patent

Des. 240,596
Patented July 20, 1976

240,596

METERED DISPENSING CONTAINER

Frank E. Brown, Burbank, Calif., assignor to SmithKline
Corporation, Philadelphia, Pa.

Filed Jan. 24, 1975, Ser. No. 543,806

Term of patent 14 years

Int. Cl. D9—01

U.S. CL. D9—169

FIG. 1.

FIG. 3.

FIG. 4.

FIG. 1 is an elevational view of a metered dispensing container showing my new design, the opposite side being the same in appearance;

FIG. 2 is an elevational view looking from the right of FIG. 1, the opposite side being the same in appearance;

FIG. 3 is a top plan view; and

FIG. 4 is a bottom plan view thereof.

I claim:

The ornamental design for a metered dispensing container, as shown and described.
